SPECIFICATION forming part of Design No. 13,884, dated May 1, 1883.

Application filed October 20, 1882. Term of patent 7 years.

To all whom it may concern:

Be it known that I, HENRY LANGER, a citizen of the United States, residing in Brooklyn, E. D., in the county of Kings and State of New York, have invented or produced a Design for Curtain or Upholstery Fabrics, of which the following is a specification.

This design relates to the ornamental configuration of the patterns woven in the strips of three-ply fabrics for curtains and upholstery goods.

This design is represented in the accompanying photograph.

Between the wider plain stripes *a b* is an ornamental stripe, composed of the narrow plain stripes *c d*, the stripes *e f*, with zigzag ornaments running along them, and the intermediate wider stripe, *m*, containing the leaflets *g*, arch scrolls *h*, rosette *i*, and radiate leaves *k*, composing the ornaments that are repeated along the stripe.

The wider stripes that form part of this fabric consist of the plain border stripes *t*.

Next to these are the border stripes *n o*, containing leaflet and lance-point ornaments.

The wider portion *r* of the stripe between the border stripes *n o* is ornamented by a design composed of the leaflets, flower ornaments, stems, and lattice background, as represented.

30 I claim as my invention—

1. The design for upholstery fabrics, composed of the ornamental stripes *e f*, leaflets *g*, arch scrolls *h*, rosettes *i*, and radiate leaves *k*, substantially as represented.

35 2. The design for upholstery fabrics, composed of the ornamental border stripes *n o* and intermediate ornamental leaflets, flowers, stems, and lattice background, as represented.

3. In a design for upholstery fabrics, the 40 combination of the plain stripes *a b c d t* and the ornamental stripes *e f m n o*, and *r*, containing the designs substantially as represented.

Signed by me this 17th day of October, A. 45 D. 1882.

HENRY LANGER.
